United States Patent Office.

E. D. CHAMBERLAIN, OF NEW YORK, N. Y.

Letters Patent No. 92,264, dated July 6, 1869.

IMPROVEMENT IN HAND-STAMPS.

The Schedule referred to in these Letters Patent and making part of the same.

To all whom it may concern:

Be it known that I, E. D. CHAMBERLAIN, of the city, county, and State of New York, have invented a new and improved Hand-Stamp; and I do hereby declare that the following is a full, clear, and exact description of the construction and operation of the same, reference being had to the accompanying drawings, making a part of this specification, in which—

Figure 1 is a side view.

Figure 2 is a top view.

The object of this invention is to provide for the common hand-stamp a simple and convenient device, which will always indicate to the eye the day of the month to which the stamp is set, without putting the operator to the inconvenience of turning the stamp bottom-up, or of taking an impression, in order to ascertain when he has turned the cylinder to the right point.

In the drawings—

A is a common hand-stamp, provided with the usual rotating-cylinders B C D, the former for the month, the latter for the year, and the intermediate one for the day of the month.

When setting these cylinders for any particular day of the month, it has heretofore been necessary to turn the stamp bottom-up, and carefully turn the cylinder until it was observed that the figures came in the right place, when, by means of the spring-pawl, or catch *p*, the cylinder was confined in that place. This process is awkward and inconvenient, and sometimes takes considerable time.

To avoid it, I employ the following-described device, which is remarkable no less for its accuracy and efficiency than for its simplicity and the ease and readiness with which it can be operated.

The figures indicating the days of the month, from 1 up to 31, are arranged at regular intervals around the disk C, and a pointer, *m*, is attached to the stamp in such a manner as to point to some place on the edge of the disk which can be clearly and conveniently seen without inverting or otherwise disturbing the stamp.

As the disk is rotated, the pointer will thus always point to some of the indicating figures. Such figure, from the fact that the spaces between numbers are

uniform, will always bear a certain relation to the number that is at the bottom of the disk and ready to give the impression.

For instance, if the pointer is so fixed (as in the drawings) that it points to the thirteenth number from that which is ready to make the impression, then, by a short calculation, we can always ascertain what day of the month will be stamped from the day to which the indicator points.

Now, to save the necessity of any calculation, and to make the matter obvious at all times, I arrange around the upper or horizontal disk F two rows of numbers, N N', each extending from 1 up to 31. The outer row indicates the number at the bottom of disk C, and ready to make the impression, and the inner row indicating the number to which the finger *m* is pointing.

For example, if disk C is fixed so as to bring the number 31 at the bottom of the disk, the pointer will point to the number 12 on the inner row of figures, such number being next to the number 31 on the outer row.

To set the stamp for any day of the month, look along the inner row of numbers for the figures immediately opposite to those indicating that day in the outer row; then turn the disk until the pointer points to the figures thus found in the inner row. The day of the month will then be at the bottom of the disk C, and the stamp will be ready for use as described.

It is obvious that the two rows of figures N N' might be arranged in an ellipse, in straight lines, or in any other form that will bring them together, so that they will answer the purpose required.

Having thus described my invention, What I claim as new, and desire to secure by Letters Patent, is—

The set card F, composed of the rows of figures N N' in combination with the frame of a hand-stamp, employing revolving printing-disks C, substantially as and for the purpose set forth.

E. D. CHAMBERLAIN.
